UNITED STATES PATENT OFFICE.

WILLIAM LORD, OF MIDDLESBROUGH, COUNTY OF YORK, ENGLAND.

VENTILATING APPARATUS.

SPECIFICATION forming part of Letters Patent No. 295,499, dated March 18, 1884.

Application filed July 16, 1883. (No model.) Patented in England March 28, 1883, No. 1,567.

To all whom it may concern:

Be it known that I, WILLIAM LORD, a subject of the Queen of Great Britain, and residing at Middlesbrough, county of York, England, 5 have invented certain improvements in apparatus for preventing downdraft in chimneys and for ventilating railway-carriages and for other ventilating purposes, (for which I have obtained a patent in Great Britain, No. 1,567, 10 dated March 28, 1883,) of which the following is a specification.

My said invention relates to apparatus to be applied to the upper part of chimneys, ventilating-shafts, or the like for the purpose of preventing downdraft and dispersing smoke and for effecting the ventilation of rooms, railway-carriages, and for other like purposes.

In carrying my invention into effect, I provide the upper part of the chimney or shaft 20 with surrounding concentric bands or rings partly overlapping each other, so that there are spaces between the overlapping parts. The chimney-top or shaft-top and each band or ring are furnished with a number of inclined blades, 25 which blades are fixed to the exteriors of the said top and bands or rings, and pass into the spaces between the overlapping parts. At the top or upper part may be fitted a plate, covering or partly covering the top and supported a short distance above or below the uppermost band or ring or level therewith.

The apparatus constructed as described may be used as a chimney top or cowl or as a ventilator; but when it is used for ventilating railway-carriages or the like the top plate will be provided with a curtain, which depends below the top of the uppermost band or ring, and the part by which the apparatus is fixed to the railway-carriage will be preferably made funnel-shaped in the interior at bottom, and be provided on its exterior with blade-springs, which, by their outward pressure when the apparatus is slipped into the opening in the railway-carriage roof, will retain the apparatus in 45 place.

Figures 1 and 2 of the accompanying drawings respectively represent in elevation and vertical section a chimney-top constructed according to my invention for preventing downdrafts and dispersing smoke, and Figs. 3 and 50 4 are respectively an elevation and vertical section of a modification of my invention fitting

it for use as a ventilator for railway-carriages or for other like purposes.

Referring to Figs. 1 and 2, A is the body of 55 the chimney-top, which, by preference, I make of a tapering or conical form, as shown.

On the upper part of the body A are secured a number of inclined blades, B, to the upper ends of which is fixed concentrically to the 60 body A a ring, band, or cylinder, C, partly overlapping the body A.

On the exterior surface of the cylinder C are fixed a number of inclined blades, D, similar to those marked B, and to the upper ends of 65 these blades is fixed concentrically to the cylinder B', and partly overlapping the same, another cylinder, E, which is also similarly provided on the exterior with inclined blades F, to the upper ends of which is attached another 70 cylinder, G, forming the crown or terminal of the chimney-top. It will thus be seen that the chimney-top is of gradually-increasing size from the bottom to the top, and that a number of annular concentric passages, *aa*, are formed 75 between the body A and the cylinder C and between the cylinders C and E and between the cylinders E and G, which passages are subdivided by the blades B, D, and F into a number of smaller passages or channels, *aa'*. The advantage of this arrangement is that a very powerful upward current of air in a direction inclined to the axis of the chimney or shaft is produced, which, acting after the manner of an ejector, creates an upward current in the 80 shaft or chimney and effects the withdrawal of any foul air or smoke that may be therein, 85 while downdraft is prevented.

I make the blades B D F to "break joint"— 90 that is to say, the end of each blade to terminate about opposite the mid part of the space between the blades next above or below it, as shown clearly in the development or spread-out view in Fig. 2^a.

I may or may not use a plate at the top, as 95 hereinbefore mentioned, and as, for example, indicated in dotted lines in Fig. 2.

The plates B, D, and F are, by preference, made with a projecting edge or lip or are trough-shaped, as shown in transverse section 100 on a larger scale in Fig. 2^b, to facilitate the upward course of the current.

The apparatus hereinbefore described may be used for ventilating railway-carriages,

churches, ships' cabins, and other structures, buildings, or rooms by arranging a cover or plate over the top or crown to prevent the entrance of rain; but I prefer to employ for ventilating purposes the arrangement illustrated by Figs. 3 and 4 of my drawings, in which the top cylinder, E, carries a top plate or dome, H, provided with a depending rim or curtain, H², to prevent the possibility of rain entering the interior of the carriage or chamber. The lower portion, A², of the apparatus is cylindrical on the exterior and provided with blade-springs a³, for the purpose of securing the apparatus in the opening provided for its reception in the roof of a railway-carriage or other place to which it is to be applied, while the interior is made funnel-shaped or conical, as shown at a², to insure the increased facility for the escape of the foul air from the interior of the carriage or apartment.

The ventilator may or may not be provided with a valve or valves, as shown in dotted lines at i, which can be turned down, when required,

by means of a handle, l². The other parts, which resemble those shown in Figs. 1 and 2, 25 are marked with the same letters of reference, the upper ring, G, and blades F being dispensed with.

I do not limit myself to the use of the number of rings or cylinders and series of blades shown, as two or more may be used for the chimney-top and one or more for the ventilator, as found convenient.

I claim—

A ventilator or chimney-top consisting of 35 two or more rings or cylinders, the upper ones being of larger diameter than the lower ones and slightly overlapping the latter, which have inclined blades on the outside, substantially as described.

WILLIAM LORD.
